UNITED STATES PATENT OFFICE.

JULIUS ALSBERG, OF NEW YORK, N. Y.

INSULATOR.

1,015,224.

Specification of Letters Patent.

Patented Jan. 16, 1912.

Application filed November 18, 1908. Serial No. 463,285.

To all whom it may concern:

Be it known that I, JULIUS ALSBERG, a citizen of the United States, residing at the city of New York, borough of Manhattan, 5 in the county and State of New York, have invented certain new and useful Improvements in Insulators, of which the following is a full, clear, and exact specification.

My invention relates to improvements in 10 means for supporting electric conductors, and the same has for its object more particularly to provide a simple, efficient and reliable device for preventing injury to the conductors or the apparatus in the circuit 15 due to an abnormal rise of potential due to lightning or other causes.

Further, said invention has for its object 20 to provide a support for electric conductors by means of which the abnormal increase of potential may be conducted from the line and caused to expend itself until the normal conditions are again restored.

Further, said invention has for its object 25 to provide an insulating support for an electric conductor having means combined therewith whereby the arcing due to such sudden rise of potential may be conducted away from the insulating member proper of the support and finally caused to rupture 30 itself or blow out.

To the attainment of the aforesaid objects and ends my invention consists in the novel 35 details of construction, and in the combination, connection and arrangement of parts hereinafter more fully described, and then pointed out in the claims.

In the accompanying drawings forming 40 part of this specification, Figure 1 is a side elevation, partly in section, showing one form of insulator constructed according to 45 and embodying my said invention, and Fig. 2 is a detail side view, partly in section, illustrating a modification.

In said drawings 5 denotes a supporting 45 arm and 6 a flexible insulating member, formed in the shape of a rope composed of strands of insulating material. The upper end of said insulating member is spliced to the body thereof to form a loop 7 having a 50 thimble 8 therein adapted to receive a hook 9 of a bolt 10 secured to said supporting arm 5 by a nut 11. The lower end of said insulating member 6 is frayed out and secured by cement or other suitable medium within 55 a conical socket 12 provided at its lower end with a loop or bail 13.

14 denotes a clamp provided with a hook or eye 15 for securing the same to the loop or bail 13 at the lower end of the insulating member 6, and 16 denotes an electric conductor secured in said clamp 14. 60

17 and 18 denote tubular protecting sections preferably made of glass, porcelain or other suitable insulating material and arranged one upon the other and surrounding 65 said insulating member 6. The protecting section 18 is provided at its lower end with an enlarged recessed portion 19 having a shoulder 20 at the base of said recess adapted to rest upon the upper or smaller end of 70 the conical socket 12, and at its upper end said protecting section 18 is provided with an outwardly projecting bead 21, and an inwardly projecting bead 22 adapted to contact with the insulating member 6 and hold 75 the same properly centered within said protecting section 18. The lower end of the protecting section 17 is also provided with an enlarged recessed end 23 which is adapted to receive the upper end of the protecting 80 section 18, and upon the outer surface of said protecting section 17, above said enlarged recessed portion 23, is provided an inwardly projecting bead 24. 25 denotes an inwardly 85 projecting bead arranged at the upper end of said tubular protecting section 17.

26 denotes a conical protecting hood made of glass, porcelain or metal or other suitable material or combinations of material and secured to the lower end of the protecting 90 section 17 above the enlarged end 23 thereof by cement or other securing means, and 27 denotes a similar hood disposed above the upper ends of the protecting section 17 and the insulating member 6 and secured rigidly in position upon the bolt 10 against the underside of the supporting arm 5. 95

28, 29 denote curved rods arranged above the conductor 16, and secured intermediate their ends by clamps 29 to the opposite 100 edges of the hood 27 with their inner ends terminating adjacent to the upper end of the protecting section 17, and their outer ends free and extending to a point above the top of the protecting hood 27. 105

When protecting hoods 26, 27 are formed of insulating material as shown at Fig. 2 conductors 30, 30 are provided extending from the curved rods 28, 28 to the bolt 10, and a conductor 31 extending from the 110 upper end of the bolt to another conductor in the line, or to the ground, should be pro-

vided, as indicated in dotted lines in the drawing.

The operation of the apparatus is as follows: Under normal conditions of line potential the insulator will serve to duly support the conductor 16 and prevent leakage therefrom. However, as soon as the potential in the line rises owing to lightning or any other abnormal conditions or disturbances which would tend to cause arcing and burn out the apparatus in the circuit, or the insulators, the current will jump from the conductor 16 to one of the curved rods 28, 28 at some points thereof, for example between the points A, B, and then travel outwardly toward the ends of said rods 28, 28 to a point, for example C, where the distance between the conductor 16 and said rod 28 is so great as to cause the arc to rupture itself. This action will be repeated as long as the abnormal potential is present in the line, and as soon as conditions return to the normal this action will cease.

It is to be noted that the operation of my improved insulator is not affected to any material extent by varying conditions of temperature and atmosphere.

In this application I have not claimed the specific construction of the insulator apart from the lightning conductor with which it is combined, as the same constitutes the subject matter of a divisional application filed December 18, 1911, Serial No. 666,392.

Having thus described my invention, what I claim and desire to secure by Letters Patent is:

1. The combination with a conductor and an insulator therefor, comprising an insulating element and a protecting hood, and a plurality of conducting members on said protecting hood arranged in the same vertical plane as said conductor and at an angle thereto, substantially as specified.

2. The combination with a conductor and an insulator therefor, of a plurality of conducting members on said insulator arranged in the same vertical plane with said conductor and at an angle thereto, substantially as specified.

3. The combination with a conductor and an insulator therefor, of a plurality of conducting members secured to said insulator adjacent to said conductor and arranged in the same vertical plane with the said conductor and at an angle thereto; said conducting members having their inner ends lowermost, substantially as specified.

4. The combination with a conductor and an insulator therefor, of a plurality of conducting members secured to said insulator adjacent to said conductor and arranged in the same vertical plane therewith, and at an angle thereto; said conducting members

having their inner ends lowermost, substantially as specified.

5. The combination with a conductor and an insulator therefor, of a plurality of conducting members secured intermediate their ends to said insulator and arranged in the same vertical plane with said conductor, and at an angle thereto; said conducting members having their inner opposing ends lowermost, substantially as specified.

6. The combination with a conductor and an insulator therefor, of a plurality of curved conducting members secured intermediate their ends to said insulator and arranged in the same vertical plane with said conductor; said conducting members having their inner ends extending downwardly and terminating in proximity to each other and their outer ends extending upwardly, substantially as specified.

7. The combination with a conductor and an insulator therefor, having a protecting hood, of a plurality of curved conducting members secured intermediate their ends to the edge of said protecting hood, and lying in the same vertical plane as said conductor, with their inner ends extending downwardly and terminating adjacent to each other, and their outer ends free and extending upwardly from the edge of said protecting hood, substantially as specified.

8. A device of the character described comprising an insulating member, means for supporting said insulating member, a series of protecting sections surrounding said insulating member, a protecting hood arranged above each of said protecting sections, and inclined conducting members secured intermediate their ends to the edge of one of said protecting hoods and extending upwardly therefrom, substantially as specified.

9. A device of the character described comprising an insulating member, means for supporting said insulating member, a series of protecting sections surrounding said insulating member, a protecting hood arranged above each of said protecting sections, inclined conducting members secured intermediate their ends to the edge of one of said protecting hoods and extending upwardly therefrom, and conductors extending from said inclined conductors to the means for supporting said insulating member, substantially as specified.

Signed at the city of New York, in the county and State of New York, this twelfth day of November, nineteen hundred and eight.

JULIUS ALSBERG.
